(57) **CLAIM**

The ornamental design for a hair styling apparatus, as shown and described.

DESCRIPTION

FIG. 1 is a perspective view of the hair styling apparatus in accordance with the principles of the present disclosure; FIG. 2 is a right side elevation view of the hair styling apparatus of FIG. 1;

FIG. 3 is a left side elevation view of the hair styling apparatus of FIG. 1;

FIG. 4 is a top plan view of the hair styling apparatus of FIG. 1;

FIG. 5 is a bottom plan view of the hair styling apparatus of FIG. 1;

FIG. 6 is a front elevation view of the hair styling apparatus of FIG. 1;

FIG. 7 is a rear elevation view of the hair styling apparatus of FIG. 1;

FIG. 8 is a perspective view of an alternate embodiment of the hair styling apparatus;

FIG. 9 is a right side elevation view of the hair styling apparatus of FIG. 8;

FIG. 10 is a left side elevation view of the hair styling apparatus of FIG. 8;

FIG. 11 is a top plan view of the hair styling apparatus of FIG. 8;

FIG. 12 is a bottom plan view of the hair styling apparatus of FIG. 8;

FIG. 13 is a front elevation view of the hair styling apparatus of FIG. 8; and,

FIG. 14 is a rear elevation view of the hair styling apparatus of FIG. 8.

The broken lines illustrate portions of the hair styling apparatus and form no part of the claimed design.

1 Claim, 6 Drawing Sheets
